UNITED STATES PATENT OFFICE.

GEORGE D. WARING AND DANIEL S. KIDDER, OF NEW YORK, N. Y., AND EDWARD W. CREECY, OF WASHINGTON, DISTRICT OF COLUMBIA.

PLAYING-CARDS.

SPECIFICATION forming part of Letters Patent No. 268,759, dated December 5, 1882.

Application filed November 13, 1882. (No model.)

To all whom it may concern:

Be it known that we, GEO. D. WARING and DANIEL S. KIDDER, both residents of the city, county, and State of New York, and EDWARD W. CREECY, residing in the city of Washington, in the District of Columbia, have jointly invented certain new and useful Improvements in Playing-Cards, of which the following is a specification.

10 Our invention is a playing-card constructed, as fully described hereinafter, so as to be available in playing any of the games for which cards are used, and also to afford an extended space for the insertion of advertisements or 15 other printed matter required for different games, &c.

In the drawings, Figure 1 is a face view of a hand of cards, showing our improvement; and Figs. 2, 3, and 4 are face views of cards 20 attached with different arrangements of printed matter.

In ordinary playing-cards the entire surface of the card is covered by the figure in the case of court-cards, while the emblems in the spot-cards are so distributed as to break up the face into small spaces, so that it is impossible to make a prominent display of any advertising or other printed matter, and if any is put upon the card it detracts from the prominence of the spots and from the utility of the card in playing. To avoid these objections we place miniature representations of the card in panels *a a'*, arranged in diagonally-opposite corners, so that by exposing either 25 corner the suit and value of the card is at once apparent, and in the wide space thus left upon the face of the card we display any advertising or other matter which it may be desired to bring to the notice of those using the cards. 30 For instance, we may insert advertisements, as shown in the drawings; or we may fill the

space with other matter intended for other games. By this construction we avoid impairing the value of the card in the least for playing purposes, and yet are able to make a most 45 prominent display of advertising-matter.

We are aware that Cyrus W. Saladee secured Letters Patent, February 9, 1864, for a playing-card having a miniature representation in one corner, and this we do not claim; 50 but such a card is not available practically in playing.

We are also aware that A. Dougherty secured Letters Patent, October 11, 1875, for a playing-card having miniature representations 55 in opposite corners and the usual emblems on the face; but such a card, having more upon its face than those ordinarily used, is less available than the latter for advertising purposes. Our above-described card can be used with 60 either end up, serves all the purposes of the conventional card, yet exposes a larger space for advertising-matter.

We claim—

A playing-card having the emblems or spots 6 arranged in small panels in diagonally-opposite corners, and an intermediate space filled with printed matter, as set forth.

In testimony whereof we have signed our names to this specification in the presence of 70 subscribing witnesses.

GEORGE D. WARING.

D. S. KIDDER.

EDWARD W. CREECY.
